UNITED STATES PATENT OFFICE.

CLARK F. RIGBY, OF BUTLER, PENNSYLVANIA.

OIL-SAVER.

1,152,549.

Specification of Letters Patent. Patented Sept. 7, 1915.

Application filed March 26, 1914, Serial No. 827,384. Renewed February 25, 1915. Serial No. 10,613.

To all whom it may concern:

Be it known that I, CLARK F. RIGBY, a citizen of the United States, and resident of Butler, in the county of Butler and State of Pennsylvania, have invented certain new and useful Improvements in Oil-Savers, of which the following is a specification.

This invention is directed to certain modifications in the casing closure of my current application, Serial No. 827,383, Mar. 26, 1914, and has particular reference to a closure for use with a sand line, the closure being adapted to be automatically released by the upward movement or pressure of the bailer or other implement secured to the line. The conditions attending the operation of bailing are such that the invention may be embodied in a closure of simpler and less expensive construction than one designed primarily for accommodating a cable for drilling tools, as in my above mentioned application, because of the greater ease with which a sand line may be extended through a casing head, and also because during the intermittent and temporary bailing periods it is unnecessary to enclose the sand line in a stuffing box as is desirable with a drilling cable.

From the foregoing it will be understood that the primary object of this invention is to provide a closure of simple construction which is capable of ready use and manipulation, and which is adapted to be released by upward pressure from beneath and be moved by the cable in advance and out of the way of the bailer as the latter emerges from the casing.

In the accompanying drawings, Figure 1 is a vertical section of the closure positioned in the casing head, showing the sand line and bailer in raised position just prior to releasing the closure. Fig. 2 is a view in top plan of the same. Fig. 3 is a sectional plan taken on line 3-3 of Fig. 1.

Referring to the drawings, 2 designates a well casing, and 3 a casing head secured at its upper end and provided with the lateral outlets 4, and above the outlets the upwardly facing seat 5. The seat is surrounded by annular flange 6 which carries the binding or set screws 7, the latter removably securing on seat 5 the annular seat-forming collar 8 which forms an upward continuation of the casing head cavity.

The casing closure consists of the annular head 9 which fits within collar 8, the up-

per portion of the head being flared outwardly at 9' to form a supporting shoulder which fits the flared upper extremity 8' of the bore of collar 8. Head 9 is formed with the central vertical passage 10 for cable C, and movable vertically in this passage and depending therefrom beneath head 9 is sleeve 11 which carries at its lower end the stop 12. The upper end of the sleeve is enlarged to form the head 11'. The sleeve constitutes a lining for passage 10, the cable operating therethrough with only sufficient clearance to prevent binding.

The beveled horizontally movable latches 13 are slidable in depression 14 which extend downwardly from the top face of head 9. The latches are held normally projected by springs 15 into position to enter annular groove 16 in the inner face of the collar 8.

Each latch is adapted to be operated by a dog 17 which is pivoted between the upstanding bearings 18 on head 9. The lower extremity 19 of the dog is entered in depression 13' in latch 13, and another extremity or offset 20 of the dog overhangs the headed upper end 11' of sleeve 11. The dogs have comparatively slight movement. When in the position shown in the drawing, the latches are projected into head-engaging position and sleeve 11 is depressed, but slight upward movement of the latter results in rocking the dogs sufficiently to retract the latches and release the closure. This release is effected by engagement of the upper extremity of bailer B or of looped lower end C' of the cable with the lower extremity of sleeve 11, so that when the bailer has been raised to the top of the well it automatically releases the closure, and the latter is withdrawn from the casing head above and along with the bailer. A spring 21 opposes upward movement of sleeve 11 and prevents gas pressure within the well from raising the sleeve and prematurely releasing the closure.

The cable C which constitutes the sand line is much smaller than a drilling cable, and is usually simply looped at its lower end through the loop B' of the bailer, no rope socket being used as is commonly employed with drilling tools. Hence, the cable or line may be readily disconnected for threading through the closure or whenever it is desired to remove the closure from the line.

The improved closure precludes the danger of accident resulting from collision of

the bailer with the casing closure, and as the closure is released automatically, the withdrawal of the bailer may proceed without interruption or slowing-down such as 5 would be necessary if there were no means for automatically releasing the closure when the bailer approaches the top of the well.

The general form of releasable closure herein disclosed is claimed broadly in my 10 above mentioned application, as is also the removable seat-forming collar 8. The advantage of the latter is that it adapts the improved closure to casing heads of standard construction, though it will be understood 15 that the invention is not limited in this regard.

I claim:—

1. The combination of a casing head, a closure therefor formed with a cable passage, latch means for detachably securing the closure to the casing head, and means movable in the cable passage and depending from the closure for actuating the latch means.

25 2. The combination of a casing head, a closure therefor having a cable passage, a plurality of latch devices for detachably securing the closure to the casing head, and a vertically movable latch-actuating means 30 common to the latches and depending beneath the closure.

3. The combination of a casing head, a casing head closure formed with a cable passage, a sleeve movable vertically in the passage and depending from the closure, and latch means operatively connected to the sleeve and adapted to detachably secure the closure to the casing head.

40 4. The combination of a casing head, a closure therefor formed with a cable passage, normally projecting latches mounted

in the closure and adapted to engage the head, dogs pivoted to the closure and operatively connected to the latches, and means for oscillating the dogs to retract the latches. 45

5. The combination of a casing head, a closure therefor formed with a cable passage, latch mechanism for securing the closure to the casing head, a sleeve movable vertically in the cable passage and depending therefrom and adapted when raised to release the latch mechanism, and a spring for opposing upward movement of the sleeve. 50

6. The combination of a casing head, a closure therefor formed with a cable passage, normally projecting latches mounted in the closure and adapted to engage the head, dogs pivoted to the closure and operatively connected to the latches, and a device movable vertically in the cable passage and operatively connected to the dogs and depending from the closure. 55

7. The combination of a casing head, a closure therefor formed with a cable passage, normally projecting latches mounted in the closure and adapted to engage the head, dogs pivoted to the closure and operatively connected to the latches, and a tubular device constituting a lining for the cable passage and movable vertically therein with the upper end of said device operatively connected to the dogs and with the lower end of said device depending beneath the closure. 60 70 75

In testimony whereof I affix my signature in presence of two witnesses.

CLARK F. RIGBY.
